(57) CLAIM

The ornamental design for a kitchen appliance, as shown and described.

DESCRIPTION

FIG. 1 is a front perspective view of a kitchen appliance, showing my new design;

FIG. 2 is a front view thereof;

FIG. 3 is rear view thereof;

FIG. 4 is a right side view thereof, the indicia being no part of the claimed design;

FIG. 5 is a left side view thereof; and,

FIG. 6 is a top plan view thereof.

The bottom view is not seen during ordinary use and is no part of the claimed design. The bowl and bowl stand depicted in light cross-hatched lines is environment and is not part of the claimed design.

1 Claim, 6 Drawing Sheets
